UNITED STATES PATENT OFFICE.

MATTHEW J. FINN, OF PITTSBURGH, PENNSYLVANIA.

PUMP.

Application filed January 25, 1922. Serial No. 531,619.

My invention relates to pumps and particularly to pumps of the rotary or centrifugal type.

My present invention is an improvement 5 upon the invention as disclosed and claimed in my Patent No. 1,397,273, dated November 15th, 1921.

In the present structure the casing is divided horizontally and the inlet and outlet 10 are in line with each other and are placed in the lower section of the casing. The lower section of the casing is also provided with removable and adjustable means for obstructing the conduit between the inlet and outlet. By the arrangement shown an improved pump is produced which is flexible 15 in operation and in which the power consumption will be substantially constant regardless of the head against which the pump works from minimum to maximum. This 20 pump will also deliver a volume of liquid substantially and inversely proportional to the variation of the head against which the pump operates.

25 My invention will be better understood by reading the following description taken in connection with the accompanying drawings forming a part thereof, in which:-

Figure 1 is a side elevation partially in 30 section of a structure embodying my invention;

Figure 2 is a vertical section on line II—II of Figure 1;

Figure 3 is a section on line III—III of 35 Figure 2;

Figure 4 is a section of a part of the impeller;

Figure 5 is a view similar to Figure 4 with wear plates attached to the impeller;

40 Figure 6 is a side elevation of a part of the impeller shown in Figure 5; and

Figure 7 is a perspective view of the means used to separate the inlet from the outlet.

45 Referring to the drawings, the pump is fastened to the base 1 by means of bolts 2.

The casing for the pump is divided into two portions 3 and 4. The portions 3 and 4 have cooperating flanges 5 and 6, respectively, which are held together by bolts 7.

The portion 3 of the casing is provided with extensions 8 and 9, as shown in Figure 2, in which are placed bearings 10 and 11 for supporting the shaft 13 to which the impeller 14 is keyed. The bearings are of any suitable construction and are provided with

the usual oil rings 15. The casing is provided with screw-threaded portions 16 into which are screwed the members 17 which surround the shaft 13 and act to compress 60 the packing 18 which surrounds the sleeve 19 keyed to the shaft 13, as shown in Figure 3.

The packing 18 is composed of the rings 20 of packing material between which are placed the metallic members 21, having channels 22 therein. Channels 23 connect channels 22 with the upper and lower portions of the chamber in which the impeller operates. By the arrangement of these channels the hydraulic pressure on the shaft due to sealing liquid is balanced and the water or other liquid being pumped acts to seal the space around the shaft and prevent the entry of air into the impeller chamber. 75

As seen from the drawings, the impeller is circular in shape and is provided on its periphery with vanes 24. The impeller is also provided with lateral wings 25. The wings 25 are provided with notches 26, the notches being in line with the spaces between the vanes as best shown in Figures 3 and 6. The portions 3 and 4 of the casing are provided with cooperating conduit sections, which when the portions of the casing 80 are in place register so as to form a conduit having a generally circular shape in which the impeller rotates. The width of the conduit is such as to receive the impeller so that the wings 25 on the impeller come in 85 juxtaposition to the side walls of the conduit, thus leaving sufficient clearance between the wings and the sides of the conduit to permit of free rotation of the impeller. The lower portion of the casing is provided 90 with an inlet opening 27 and an outlet opening 28, which is in line with the inlet. I have found that the best results are secured by making the taper of the sides or walls of the inlet and outlet from about 3° to 6° from 95 the center line thereof. The preferred slope is about 4½°. The inlet and outlet are separated by a member 29, which may be removable and adjustable, as shown in Figure 3, or may be integral with the casing of the 100 machine. This member 29 is placed in a recess in the portion 3 of the casing and is held in place by countersunk bolts 30. The member 29 has upstanding flanges 31, thus leaving a space therebetween through which 105 the vanes on the impeller pass. The flanges 31 are arranged so that they closely fit the

edges of the vanes, as shown in Figure 2, and the depth of the space between the flanges is such as to closely fit the outer ends of the vanes. By this arrangement the conduit is obstructed between the inlet and outlet so that the fluid being pumped must pass from the inlet around the circumference of the conduit and out at the outlet. This enables the impeller to raise the pressure of the fluid and transmit the same.

If the pump is used to handle sandy or gritty fluid, it might happen that the edges of the wings 25 would become slightly worn. Such wear would produce a space between the edges of the wings and the casing through which the liquid would pass and as a result of which the original pressure generated by the pump would decrease. In such event the wear plates 32 may be applied to the wings, as shown in Figures 5 and 6. That is to say, the portion 33 is forced underneath the wings, thus leaving a thin portion 34 on the edges of the wings. The thickness of the portion 34 may be any desired amount and the wear plates are applied to the impeller in much the same manner that the lid is applied to a can and the wear plates are held in place by friction between the portions 33 and the lower sides of the wings.

After the pump has been in operation for some time on sandy or gritty fluid, the impeller or the member 29 may become worn so as to allow an undesirable leakage between the inlet and outlet. In order that this difficulty may be overcome, I have provided means whereby the member 29 may be adjusted radially with respect to the impeller. The means shown comprise shims 35 placed below the member 29 in the depression in which that member rests. By adding a shim of the required thickness the member 29 is brought into proper relation with the impeller.

From the foregoing description the operation of my device will be understood without a detail description thereof.

My invention has many advantages in addition to the advantages set forth in my patent above referred to, in that separate means are provided whereby the wear on the sides of the impeller may be compensated for; simple means are provided whereby the wear between the impeller and the partition 29 may be compensated for; the casing is divided horizontally and the inlet and outlet are in line with each other as a result of which a greater pressure is developed because the liquid is under the influence of the impeller for a greater arc of its rotation; means are provided for balancing the hy-

draulic pressure on the shaft and for acting as a water seal to prevent the entry of air into the working chamber.

While I have shown and described in detail one embodiment of my invention, I desire it to be understood that I am not to be limited to the exact details shown and described, as many changes may be made without departing from the spirit of my invention.

I claim:

1. A pump, comprising an impeller having vanes on the periphery thereof, means extending laterally from each side of said impeller near the base of said vanes for throwing the fluid outwardly, a shaft for the impeller, a casing having a chamber in which said impeller rotates and being divided horizontally along a plane passing through the shaft, said casing being provided with an inlet to and an outlet from said chamber, said inlet and outlet being in line with each other, means separating said inlet from said outlet and free from contact with the impeller and having a channel through which said vanes move and said casing being in close proximity to the edges of said laterally extending means to form a substantially closed channel enclosing said vanes, and means whereby said separating means may be adjusted radially towards and from said impeller.

2. A pump, comprising an impeller having vanes on the periphery thereof, wings extending laterally from each side of said impeller near the base of said vanes for throwing the fluid outwardly, a shaft for the impeller, a casing having a chamber in which said impeller rotates and being divided horizontally along a plane passing through the shaft, said casing being provided with an inlet to and an outlet from said chamber, said inlet and outlet being in line with each other, means separating said inlet from said outlet and free from contact with the impeller and having a channel through which said vanes move, said casing being in close proximity to the edges of said laterally extending wings to form a substantially closed channel enclosing said vanes, means whereby said separating means may be adjusted radially towards and from said impeller, and means whereby the wings of the impeller may be adjusted laterally towards and from the side walls of the pump casing and radially towards and from the separating means.

In testimony whereof I have hereunto set my hand.

MATTHEW J. FINN.
